UNITED STATES PATENT OFFICE.

IRVIN SALTSMAN AND ELIJAH SALTSMAN, OF AVOCA, NEW YORK.

POTATO-DIGGER.

SPECIFICATION forming part of Letters Patent No. 365,865, dated July 5, 1887.

Application filed January 18, 1887. Serial No. 224,712. (No model.)

To all whom it may concern:

Be it known that we, IRVIN SALTSMAN and ELIJAH SALTSMAN, citizens of the United States, residing at Avoca, in the county of Steuben and State of New York, have invented a new and useful Improvement in Potato-Diggers, of which the following is a specification.

Our invention relates to an improvement in potato-diggers; and it consists in the peculiar construction and combination of devices, that will be more fully set forth hereinafter, and particularly pointed out in the claims.

In the drawings, Figure 1 is a side elevation of a potato-digger embodying our improvement. Fig. 2 is a top plan view of the same. Fig. 3 is a vertical longitudinal sectional view taken on line $x-x$ of Fig. 2.

A represents a rectangular frame, which is provided on its under side near the center with bearing-boxes B, in which is journaled a transverse shaft, C, the latter being free to move endwise in the boxes, for the purpose to be hereinafter set forth. To the ends of the said shaft are attached driving and supporting wheels D, and at suitable distances from the center of the shaft are rigidly secured miter gear-wheels E and E', the toothed edges of which are opposed to each other.

F represents a shifting-lever, which is fulcrumed to the frame A, and has its short end connected to a sleeve, G, that is secured upon the shaft C, and in which the latter rotates. The front end of the frame is provided at its corners with forwardly-projecting bracket-ears H, through which extends a transverse bolt-rod, I, the ends of which project beyond the outer sides of the bracket-ears.

K represents the tongue, the rear end of which is provided with a cross-bar, L, having depending ears which are pivoted upon the bolt-rod I.

M represents a rearwardly and upwardly extending frame comprising the two bent bars N, having their front ends attached to the upper side of the frame A and the brace-bars O, the ends of which are attached to the bars N, the central portions of the front brace-bar being firmly attached to the rear end of the frame A. On the upper horizontal portions of the bent rods N is secured a transverse board, O', which forms a seat for the driver. From the central

portion of this board, on the upper side thereof, projects an inverted U-shaped keeper, P, and alongside the said keeper is a projecting lug, R.

S represents a rod, which is connected at its front end to an ear or lug that projects from the upper side of the tongue near the rear end thereof. The rear portion of the said rod S extends through the keeper P, and is provided with a pivoted detent, T, which is adapted to be turned upwardly, so as to engage the keeper P, and thereby support the tongue at a suitable angle to the frame A, instead of in a position parallel therewith.

U represents a longitudinal shaft, which is journaled in suitable bearing-blocks secured on the under side of the frame A at the center and at the rear end thereof. The front end of this shaft U is provided with a rigid miter-pinion, V, that is arranged between the gear-wheels E and E', and is adapted to engage either of the said gear-wheels when the shaft C is moved endwise by means of the shifting-lever F. To the rear end of the shaft U is attached a reel, W, comprising a central circular disk, X, and radial arms Y, which project therefrom and have their outer ends curved forwardly, as shown. The diameter of this reel is such that when the frame A is in a horizontal position the ends of the arms on the lower side of the reel will be below the surface of the earth.

Z represents a sleeve, which has its rear end attached to the front side of the central disk, X, the said sleeve projecting forwardly and surrounding the shaft U and rotating therewith, for the purpose to be hereinafter explained.

From the under side of the tongue K, near the rear end thereof, depend ears A', through which extend a transverse pivotal bolt, B', the ends of which project beyond the said ears.

C' represents a pair of curved teeth or colters, each of which is made from a round bar of metal bent in the form shown in Figs. 1 and 3, and having its upper end curved to form an eye, whereby the tooth or colter may be pivoted on the bolt B'. A U-shaped yoke, D', is attached to the ends of the pivotal bolt, and thereby secures the teeth or colters from

becoming accidentally detached therefrom, and one side of the said yoke is provided with an upwardly-extending arm, to which is pivotally connected the front end of a rod, E². Near the rear end of the said rod is a projecting offset or shoulder, E³, which is adapted to engage the ear R on the seat-board O.

F' represents inclined draw-bars, which are provided at their front ends with upturned arms G', having each a vertical series of openings, which are adapted to receive the projecting ends of the bolt-rod I, and thereby the front ends of the draw-bars are vertically adjustable with relation to the front ends of the frame A. From the rear ends of the draw-bars depend vertical standards H', to the outer sides of which are attached diagonally-arranged plows or cutters I', the faces of which are turned outwardly, and thereby the said cutters are adapted to throw the earth outwardly toward the wheels B as the machine advances.

K' represents stay-rods, which have their lower ends attached to the rear ends of the draw-bars F', the upper ends of the said stay-rods being provided with vertical series of openings, and are thereby adapted to be attached to the sides of the frame A and vertically adjusted thereon by means of bolts, as shown, so as to cause the plows or cutters to run in the ground at any desired depth. By vertically adjusting the front ends of the draw-bars, as before described, the angle or pitch at which the plows or cutters enter the ground 35 may be regulated at will.

L' represents a curved scoop, the front cutting-edge of which is curved or beveled on opposite sides, as shown at Fig. 2, and the ends of the said scoop are upturned to form ears M'.

N' represents draft-rods, which have their front ends attached to the lower ends of the standards H'. At a suitable distance from the rear end of each draft-rod is an opening, N², and at the extreme rear end of each draft-rod 45 is a curved slot, N³, the radius of which is drawn from the center of the opening N². Suitable bolts are passed through the ears of the scoop and through the openings N², so as to pivotally secure the scoop to the rear ends of the draft-rods, and clamping-bolts extend 50 through the ears of the scoop and work in the curved slots N³, the function of the said clamping-bolts being to secure the scoop at any desired inclination at the rear ends of the draft-rods.

The operation of our invention is as follows: A team of horses is hitched to the tongue, and the driver, seated upon the seat-board O, directs the team so as to cause the wheels D to 60 run astride of the row of potatoes to be dug. The teeth or colters are lowered to the ground and caused to work therein on each side of the row, the function of the said teeth or colters being to straighten the vines and dispose 65 them in substantially parallel rows in advance of the scoop. The plows or cutters I' cut the

sides of the furrow, which is subsequently made by the scoop, thereby preventing the corners formed by the junction of the ends of the latter with the draft-rods from becoming 70 fouled with earth or trash, and as the scoop is drawn forward it buries itself in the earth under the potatoes and digs the latter. When the machine is started, the shifting-lever is moved, so as to cause one of the gear-wheels 75 E and E' to engage the pinion V, and thereby the shaft U is rotated, and thus a rotary motion is imparted to the reel. As the potatoes are dug by the scoop, they fall upon the rapidly-rotating arms of the reel, and are thoroughly sifted by the latter and separated from adhering earth and the vines, and are left upon the top of the earth in rear of the machine. The loose dirt and vines are thrown to one side of the row by the whirling motion 80 of the arms of the reel. When the machine is run in the next adjacent row, the shifting-lever is moved so as to cause the rotating of the reel to be reversed, and thus prevent the reel from throwing the loose earth and vines onto the 85 potatoes in the first row which have been already dug and cover them up. When the machine is being driven across the field or along the road and is not in operation, the driver grasps the rear end of the rod S and 90 moves the same rearwardly sufficiently far to cause the detent to engage the keeper P. This causes the rear end of the frame A to be raised, so as to raise the scoop above the surface of the earth. The rod E² is also drawn rearwardly 95 and secured upon the ear T, so as to raise the front ends of the teeth or colters above the ground. The function of the sleeve Z is to prevent the vines from becoming wound upon the shaft U, and thus causing the latter to 100 cease to rotate.

Having thus described our invention, we claim—

1. A potato-digger having teeth or colters pivotally secured to the tongue on the under side thereof, and a lever connected to said teeth or colters to raise and lower the same, substantially as set forth.
2. In a potato-digger, the combination of the sulky-frame, the draw-bars attached thereto and provided with plows or cutters, and the scoop connected to said draw-bars in rear of the plows or cutters, substantially as specified.
3. In a potato-digger, the combination of the sulky-frame, the draw-bars adjustably attached thereto, and the scoop adjustably secured to said draw-bars and moving therewith, substantially as set forth.
4. In a potato-digger, the combination of the sulky-frame A, the draw-bars attached thereto and having their front and rear ends independently adjustable, and the scoop connected to the said draw-bars and movable therewith, substantially as described.
5. In a potato-digger, the combination of the draft-rods and the scoop pivotally attached

thereto and adjustable to any desired pitch, substantially as described.

6. In a potato-digger, the combination of the draft-rods having the curved slots, the 5 scoop pivoted between the said draft-rods, and the clamping-bolts projecting from the scoop and working in the curved slots to adjust the scoop at any required angle, substantially as described.

10 7. In a potato-digger, the combination of the sulky-frame, the scoop connected thereto, the tongue pivotally connected to the frame, and the lever or rod to adjust the frame at an angle to the tongue, for the purpose set forth, 15 substantially as described.

8. In a potato-digger, the teeth or colters to straighten the vines, in combination with the plows or cutters, the scoop in rear of the latter, and the rotating reel, as set forth.

In testimony that we claim the foregoing as 20 our own we have hereto affixed our signatures in presence of two witnesses.

IRVIN SALTSMAN.
ELIJAH SALTSMAN.
